UNITED STATES PATENT OFFICE

153,091

DESIGN FOR A CERAMIC VASE OR SIMILAR ARTICLE

Alwin L. Suman, Sierra Madre, Calif.

Application August 17, 1946, Serial No. 132,614

Term of patent 3½ years

(Cl. D29—28)

To all whom it may concern:

Be it known that I, Alwin L. Suman, a citizen of the United States, and residing at Sierra Madre, in the county of Los Angeles, State of California, have invented a new, original, and ornamental Design for Ceramic Vase or Similar Article, of which the following is a specification, reference being had to the accompanying drawing, forming part thereof, in which:

Fig. 1 is a perspective view of a ceramic vase or similar article, showing my new design,

Fig. 2 is a side elevation thereof, and

Fig. 3 is a top plan view of the ceramic vase or similar article as shown in Figs. 1 and 2.

I claim:

The ornamental design for a ceramic vase or similar article, substantially as shown.

ALWIN L. SUMAN.
